US00D772940S

(12) **United States Design Patent** (10) Patent No.: **US D772,940 S**
(45) Date of Patent: **** Nov. 29, 2016**

(54) **DISPLAY SCREEN OR PORTION THEREOF WITH ICON**

(71) Applicant: **Apple Inc.**, Cupertino, CA (US)

(72) Inventors: **Joe Marianek**, San Francisco, CA (US); **Wan Si Wan**, Sunnyvale, CA (US); **Christopher Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/565,199**

(22) Filed: **May 18, 2016**

Related U.S. Application Data

(63) Continuation of application No. 29/457,326, filed on Jun. 9, 2013, now Pat. No. Des. 757,737.

(51) **LOC (10) Cl.** **14-04**
(52) **U.S. Cl.**

USPC **D14/492**
CPC **G06F 3/04817** (2013.01)

(58) **Field of Classification Search**

USPC D14/485-495; 715/700-867, 973-977
CPC G06F 3/0481-3/0486
See application file for complete search history.

(57) **CLAIM**

The ornamental design for a display screen or portion thereof with icon, as shown and described.

DESCRIPTION

The FIGURE is a front view of a display screen or portion thereof with icon showing our new design.

The broken lines in the FIGURE show a display screen or portion thereof, and form no part of the claimed design.

1 Claim, 1 Drawing Sheet
